Inventor

ROBERT M. EVANS

By Attorney

Richard J. Cook

UNITED STATES PATENT OFFICE.

ROBERT M. EVANS, OF SEATTLE, WASHINGTON.

SPLICE SHOE.

Application filed January 17, 1922. Serial No. 529,952.

To all whom it may concern:

Be it known that I, ROBERT M. EVANS, a citizen of the United States, and a resident of the city of Seattle, county of King, and 5 State of Washington, have invented certain new and useful Improvements in Splice Shoes, of which the following is a specification.

This invention relates to improvements in 10 rail splice shoes for portable track sections, and has for its principal object to provide a spliced shoe whereby the ends of rails may be easily and quickly joined and which is constructed in such manner that its opposite side flanges or fish plates may be tightened 15 against the opposite side of the rail to which it is permanently fixed, to provide a rigid and satisfactory connection.

A further object of the invention resides 20 in the provision of a splice shoe that will substantially support the ends of rails that are joined thereby, which provides for the discharge of dirt from between the rail ends when the parts are assembled, and which 25 permits easy insertion of the rail.

In accomplishing these and other objects 30 of the invention, I have provided the improved details of construction, the preferred forms of which are illustrated in the accompanying drawings, wherein—

Figure 1 is a side elevation of a splice shoe constructed in accordance with the present invention, illustrating the manner in which it is used to support and connect 35 the ends of rails of track sections.

Figure 2 is an under side, plan view of the splice shoe, particularly illustrating the extension of the base slot.

Figure 3 is a transverse section, taken on 40 the line 3—3 in Figure 1.

Referring more in detail to the drawings—

1 and 2 designate respectively the adjacent ends of rail sections that are joined by 45 means of a splice shoe 3 constructed in accordance with the present invention.

The shoe 3 consists of a single casting having a flat, horizontal base portion 4 which underlies the base flanges of the rails 50 and which is provided centrally with a longitudinal slot 5, as shown in Figure 2, which opens at one end of the shoe and extends to near the opposite end.

Integral with the base portion, are opposite side flanges or fish plates 6 and 7 which 55 are directed inwardly to fit about and over the base flanges of the rails 1 and 2, and are then extended upwardly and seat against opposite faces of the webs of the rails and, at their upper edges, are seated against the 60 under sides of the rail heads. Apertures 8 are provided in these fish plates which are adapted to register with apertures through the webs of the rails and to receive a bolt 9 therethrough whereby parts can be joined 65 together. It is desired to slightly flare the plate at one end of the shoe, as is indicated at 10 in Figure 2, and to slope the upper edges of the flared portions, as at 11, so that the rail at this end can be pushed easily into 70 position. If it is desired, both rails may be secured to the shoe but this is not ordinarily done.

With the shoe so constructed, it is apparent that when the nut of the bolt 9 is 75 tightened, the opposite side plates of the shoe will be drawn tightly against the opposite side of the web of the rail and the shoe will be held rigidly and securely in 80 position. This is possible, due to the flexibility in the shoe provided by the elongated slot in the base portion.

Having thus described my invention, what I claim as new therein and desire to secure by Letters Patent, is:

1. A device of the class described, comprising a pair of fish plates connected by an integral, horizontal base plate, having a longitudinal slot opening at one end thereof, and extending to near the opposite end, said 90 fish plates having apertures therethrough for receiving bolts for the purpose set forth.

2. A splice shoe of the character described comprising a base plate for underlying the ends of rails joined thereby and having opposite side flanges adapted to extend along 95 opposite sides of the webs of the rails; said base plate having a longitudinal slot therein opening at one end of the base and extending to near the other end of the shoe, and, said side flanges having apertures therein through which a bolt may be extended to 100 tighten the flanges against the rails.

Signed at Seattle, Washington, this 12th day of January, 1922.

ROBERT M. EVANS.
